UNITED STATES PATENT OFFICE.

JEAN JULES MARIE ANTOINE EUGÈNE SCHNEIDER, OF PARIS, FRANCE.

APPARATUS FOR REGULATING THE EFFECTIVE SURFACE OF THE RADIATORS OF AEROPLANE-ENGINES.

1,374,610.

Specification of Letters Patent. Patented Apr. 12, 1921.

Application filed February 28, 1920. Serial No. 362,122.

To all whom it may concern:

Be it known that I, JEAN JULES MARIE ANTOINE EUGÈNE SCHNEIDER, a citizen of the Republic of France, and resident of Paris, France, have invented new and useful Improvements in Apparatus for Regulating the Effective Surface of the Radiators of Aeroplane-Engines, which invention is fully set forth in the following specification.

10 This invention has for its object to provide an improved apparatus for regulating the effective surface of the radiators of aeroplane engines.

15 The improved apparatus comprises a movable screen and is so constructed that in any position it will offer only a minimum resistance to the progress of the aeroplane.

According to this invention the screen is constituted by a sheath of metal plate or 20 other suitable materials and has a fusiform cross section and is adapted to slide longitudinally along the radiator so as to be caused to cover a greater or less extent of the latter. For this purpose a guide for the said 25 sheath is provided on the radiator body.

According to one embodiment of this invention the guide for a sliding member fixed to the sheath of fusiform section, is constituted by pads that inclose the water boxes 30 and have likewise a fusiform cross section. By means of these fixed pads that inclose the water boxes of the radiator, the combination of the latter and the movable screen can be supported on the aeroplane.

35 Figures 1 to 4 of the accompanying drawings illustrate a first constructional form of this invention.

Figs. 1 and 1^a together constitute a front elevation of the radiator with the invention 40 applied thereto, Fig. 1 showing the radiator in masked position and Fig. 1^a in unmasked position.

Fig. 2 shows one of the elements of the mask partly in elevation and partly in longitudinal section.

45 Fig. 3 is a horizontal section on the line 3—3 of Fig. 2.

Fig. 4 is a diagram of a device for operating the two elements of the mask by means 50 of a common drive.

Figs. 5 and 5^a together constitute another form of the invention, showing the same in

front elevation, Fig. 5 showing the radiator unmasked and Fig. 5^a showing the same masked.

Fig. 6 is a vertical section on the line 6—6, and Fig. 7 is a horizontal section on the line 7—7, of Fig. 5.

In Figs. 1 to 4, A is the body of a radiator of known construction shown diagrammatically. B and B¹ are respectively the upper and lower water boxes.

The mask is composed of two elements C arranged symmetrically in relation to the plane of the axis a—a. Each of these elements consists of a sheath of metal plate having a fusiform cross section (Fig. 2). These sheaths constitute casings closed on the outer side by a solid end c of suitable cross section for facilitating the flow of the air. On the inner side the opposite end c¹ is recessed in such a manner as to engage with a slight amount of play the body A of the radiator and the pads D, D¹ in which the water boxes B, B¹ are inclosed. These pads extend the whole length of the corresponding boxes. They have a fusiform cross section (Fig. 2) and are recessed and so constructed as to serve as slideways d, d¹ for sliding members E, E¹ fixed to the sheaths C. 80

The girder-shaped sliding members E, E¹ are of course made of suitable length as shown in Fig. 1, to allow the inner ends e, e¹ of the elements to have a sufficient length of course until they meet each other in the axial plane a—a, while assuring for the said members the desired fixing in the unmasked position of the radiator.

The whole of the radiator and the masks may be supported on the aeroplane by a suitable attachment of the pads D, D¹ to the framework of the aeroplane. The inclination of the pads D, D¹ to each other may be varied so as to give to the sort of funnel-shaped passage which they form for the entry and flow of the air, the desired converging or diverging shape.

The moving of the elements C toward each other for the purpose of diminishing the effective surface of the radiator as well as the moving of these elements away from each other for the reverse purpose, may be effected by means of any suitable actuating mechanism; for instance each element C

may be provided as shown in Fig. 4 with an attachment for a rope $f-f'$ guided by means of fixed pulleys G, H and I.

If the stretch of rope f (shown in full lines) is pulled in the direction of the arrow 1, this will have the effect of moving the points of attachment F nearer to each other, and consequently bringing the sheaths C into the position shown in the left hand portion of Fig. 1 wherein they mask a portion of the radiator, or into any other intermediate position. A pull exerted upon the stretch of rope f' (indicated in dot and dash lines) in the direction of the arrow 2, will have the effect of moving the points of attachment F away from each other.

Figs. 5, 6 and 7 illustrate another embodiment of this invention wherein each of the sheaths, instead of being formed by a casting slideable as a whole, comprises a fixed element outside the radiator, and into which element the mask proper composed of telescopic elements is adapted to be moved into inoperative position.

Fig. 5 illustrates in its left hand half partly in section partly in elevation the left hand mask rendered inoperative by moving into the outer fixed element of the sheath. In the right hand half of this figure the mask is shown fully opened out.

Each sheath comprises a fixed element C outside the radiator, adapted to be attached to the water boxes of the latter by suitable attachment devices, such as for instance the angles J. The outer ends of these angles may be fixed to a reinforcing girder of the fixed element C, as shown in the drawing. Their inner ends together with the water boxes B, B' are adapted to serve as guides for angles c^2 that are fixed to the inner wall of the extreme inner sheath elements C^2 .

An actuating mechanism similar to the one described for use with the preceding construction or any other suitable mechanism, may comprise for the rope $f-f'$ attaching eyelets formed on one end of rods

that are fixed at their other ends to the inner sheath element C^2 .

That what I claim is:

1. In an apparatus for regulating the effective surface of the radiators of aeroplane engines, the combination of a radiator body, a guide thereon, a stream-lined sheath slidably mounted on said guide to inclose the radiator body, and means for actuating said sheath in either direction on said guide to inclose the radiator body more or less.

2. In an apparatus for regulating the effective surface of the radiators of aeroplane engines, the combination of the radiator, upper and lower water boxes thereon, pads on said boxes having slideways formed therein, a sheath having sliding engagement with said slideways, and means for actuating said sheath in either direction on said slideways.

3. In an apparatus for regulating the effective surface of the radiators of aeroplane engines, as claimed in claim 1, a sheath composed of a plurality of telescoping elements, the larger outer element being attached to the guide on the radiator body and serving as a guide for the smaller inner element.

4. In apparatus for regulating the effective surfaces of the radiators of aeroplane engines, the combination of a radiator body, and a stream-lined sheath movable over the radiator body to inclose the same.

5. In apparatus for regulating the effective surface of the radiators of aeroplane engines, the combination of a radiator body, and a stream-lined sheath composed of a plurality of telescopic elements extendible over the radiator body to inclose the same.

In testimony whereof I have signed this specification.

JEAN JULES MARIE ANTOINE EUGÈNE SCHNEIDER.
